Hand of the Devil

Des. 840

J. M. Gibbs, of Albany, N.Y.
Assignor to
North, Chase, & North, of Philadelphia, Pa.
Letters Patent No. 840. Dated October 7, 1856.

The Schedule referred to in these Letters Patent, and making part of the same.

To all whom it may concern,

Be it known that I, S. W. Gibbs, of the City and County of Albany, and State of New York, have invented or produced a new and original design for stoves, and I do hereby declare that the following is a full and exact description of the same, reference being had to the accompanying drawings, making part of this specification, in which:

Fig. 1, represents a perspective elevation of the stove.

a, is an ornamental border for the top plate. b, is an ornamental border or cap for the upper cylinder. c, is an ornament for the lower border of the upper cylinder. d, is an ornamental door. e, is an ornamental upper border for the lower cylinder. f, is an ornamental border for the ash pit. g, is an ornamental border for the hearth plate. h, is a foot.

What I claim, as my invention, and desire to secure by Letters Patent, is the design and configuration of the ornaments, as herein described, forming an ornamental design for stoves.
